BRASSIÈRE HALTER

Edwin W. Gluckin, Rockville Centre, N. Y., assignor to Wm. Gluckin & Co., Inc., New York, N. Y.

Application May 3, 1950, Serial No. 9,680

Term of patent 3½ years

(Cl. D20—4)

To all whom it may concern:

Be it known that I, Edwin W. Gluckin, a citizen of the United States of America, residing at Rockville Centre, in the county of Nassau and State of New York, have invented a new, original, and ornamental Design for a Brassière Halter, of which the following is a specification, reference being had to the accompanying drawing, forming part thereof.

In the drawing

Fig. 1 is a front perspective view of a brassière halter showing my new design, the same being illustrated as it appears when worn;

Fig. 2 is a rear view of said brassière halter as it appears when its ends are separated and spread apart, one of said ends being twisted; and

Fig. 3 is a front view of the brassière halter as it appears when doffed.

I claim:

The ornamental design for a brassière halter, substantially as shown and described.

EDWIN W. GLUCKIN.
